[57] CLAIM

The ornamental design for a word processor, as shown and described.

DESCRIPTION

FIG. 1 is a front, top and right side perspective view of a word processor showing our new design;

FIG. 2 is a front elevational view thereof on an enlarged scale;

FIG. 3 is a rear elevational view thereof on an enlarged scale;

FIG. 4 is a top plan view thereof on an enlarged scale;

FIG. 5 is a bottom plan view thereof on an enlarged scale;

FIG. 6 is a right side elevational view thereof on an enlarged scale;

FIG. 7 is a left side elevational view thereof on an enlarged scale;

FIG. 8 is a front, top, and right side perspective view thereof on an enlarged scale, with the cover closed.

FIG. 1

FIG. 2

FIG. 3

FIG. 4

FIG. 5

FIG. 6

FIG. 7

FIG. 8
